FEEDING APPARATUS

Robert H. Lawson, Pawtucket, R. I., assignor to
 Scott & Williams, Inc., Laconia, N. H., a corporation of Massachusetts

Application March 23, 1938, Serial No. 197,749

5 Claims. (Cl. 242—147)

This invention relates to feeding apparatus.

It is a primary object of the invention to provide apparatus for positively feeding material under substantially uniform tension irrespective of the nature of the material or of the speed at which it is moved. The tension desired may be almost negligible or may be considerable depending upon the kind of material being fed and what happens to it beyond the apparatus of this invention. The normal speed of travel of the material may be either constant or variable, in either event it is a feature of the invention to positively feed the material at a speed determined by the demand for it.

The principles of the invention are herein disclosed in their particular application to the feeding of yarn, but this is merely illustrative and not limiting. In one embodiment shown the yarn being fed is representative of rather delicate and practically unstretchable material which can be subjected to only a very light tension. In another illustrative example the yarn being fed is representative of strong and greatly stretchable material which can be fed at a comparatively high tension. These embodiments, as before stated, are to be taken as merely illustrative of the best mode in which I have contemplated applying the principles of my invention for it is intended that the patent shall cover by suitable expression in the appended claims whatever features of patentable novelty exist in the invention as a whole.

In the accompanying drawings:

Figure 1 is a front elevation of apparatus embodying my invention particularly adapted to the feeding of small delicate yarn;

Figure 2 is a side elevation, looking from the right toward Figure 1;

Figure 3 is a diagrammatic showing of a simple electric circuit employed in my apparatus;

Figure 4 is a plan taken partly in section as on line 4—4 of Figure 1;

Figure 5 is an elevation partly in section as on line 5—5 of Figure 4;

Figure 6 is a sectional elevation taken as on line 6—6 of Figure 4;

Figure 7 is a sectional elevation taken as on line 7—7 of Figure 2;

Figure 8 is a front elevation showing how the feed gears may be adjusted for different sizes of yarn;

Figure 9 is a side elevation showing feed rolls for feeding light rubber yarn;

Figure 10 is a front elevation of the elements shown in Figure 9;

Figure 11 is a front elevation, similar to Figure 1, showing an added feature;

Figure 12 is a front elevation, similar to Figure 1, showing a feature which may be employed to take up slack in the yarn;

Figure 13 is a side elevation of parts of Figure 12;

Figure 14 is a front elevation showing the adaptation of the invention for feeding strong and greatly stretchable rubber yarn at high tension;

Figure 15 is an enlarged front elevation of certain details of Figure 14;

Figure 16 is a plan view of the details of Figure 15;

Figure 17 is a sectional elevation taken as on line 17—17 of Figure 15;

Figure 18 is a side elevation of other details of Figure 14; and

Figure 19 is a rear elevation of the details of Figure 18.

Referring now to the drawings and particularly to Figures 1 to 8 inclusive, the apparatus shown in these figures is especially applicable to the feeding of rather delicate material which should be subjected to but very light tension, for example the yarn which might be used in a knitting machine. Such yarn A is illustrated as coming from any convenient source of supply (not shown) and passing through a guide 20, then between feed gears 22, 24 and thence through the ring end 26' of a rather long light element 26, whence the yarn passes along to the machine by which it is processed. The feed gears 22, 24 are driven by an electric motor 28 mounted on a bracket 30 secured to any convenient support 32 such as a part of the frame of the machine using the yarn. As shown, the gear 24 is secured to the shaft of the motor and is driven directly. The other gear 22 is mounted on a shaft 34 carried by an arm 36 which is adjustable on the bracket 30 by virtue of a pivot pin 38, slot 40, and clamp bolt 42. As shown in Figure 1, the adjustment of the arm 36 and the gear 22 is for a thin yarn A, while in Figure 8, the adjustment of the same parts is for a comparatively thick yarn A'.

The current for the electric motor 28 is supplied thereto from any convenient source by way of a rheostat 44 shown mounted on a depending L-shaped arm 46 which in turn is rigidly supported by distance sleeves 48 and bolts 50 to a straight arm 52 extending downward from bracket 30. This L-shaped arm 46 is made of non-conductive material such as Bakelite or the like and at the end of its horizontal portion 46a (see 53

Figures 4-5-6) has an off-set portion 46b constituting a hub. Extending through this hub and pinned thereto at 54 is an axle 56 having good electrical conductivity, and around the hub 46b, between its flanged sides 46c and 46d, are a series of small rods 58, also of good electrical conductivity. These rods 58 are individually connected by wires 60 with the elements 44a of the rheostat.

10 Rotatably supported on the axle 56 is a yoke arm 62 on which is secured by clamp screw 64 a strip of resilient metal 66 which is a good conductor of electricity. One end 66a of this strip is hooked around the exposed end 56a of the axle and the other end 66b is curved and extended over the rods 58 so as to rest on only one of them at a time. This yoke arm 62 also carries the element 26, previously mentioned, which terminates in the ring end 26' that engages the material being fed. To the axle 56 is secured a wire 68 leading from a source of electrical supply. The circuit for the motor can now be readily traced, being shown diagrammatically in Figure 3. From the source of electric current the lead wire 68 connects with the axle 56. The current then passes by way of the resilient strip 66 to one of the bars 58, thence by its connecting wire 60 to the rheostat 44 and thence by wire 70 to the motor. From the motor another wire 72 connects with the source of supply.

30 The speed of the motor is controlled by the amount of current reaching it from the rheostat 44 and the effectiveness of the rheostat is determined by the contact between the end 66b of the resilient strip 66 with one of the rods 58. As shown in Figure 5, the strip is in contact with the fourth rod 58, starting from the right and counting in an anti-clockwise direction. This contact means a certain speed of the motor depending upon the effect imposed by the rheostat. If the brush end 66b moves counterclockwise to make successive contacts with each successive rod 58, the motor will speed up, as each contact in a counterclockwise direction means a greater supply of current to the motor. If the brush end 66b reaches the endmost rod 58 in its counterclockwise movement, the circuit is fully opened to the motor by way of the wire 74 which bypasses, as it were, the rheostat 44. Reversely, movement of the brush end 66b in a clockwise direction reduces the speed of the motor as each successive rod 58 is contacted. In the drawings, the particular rheostat 44 shown has only five stages, but this is to be understood as representative of a rheostat having as many stages as there are rods 58 on the hub 46, except that the last rod 58a on the right-hand end of the series has no electrical connection whatever with the rheostat or motor. Although I have particularly disclosed and described a rheostat as the means for effecting a change in the speed of the motor, this is to be understood as merely illustrative of suitable means for varying the motor speed.

65 This last rod 58a is so located that when it is in contact with the end 66b of the resilient strip, the yoke arm 62 and element 26 will be in the position P1 indicated in dotted outline in Figure 5. When this position is reached, the circuit to the motor is broken and in the embodiment of the invention shown in Figures 1, 2, 7 and 11, a brake is applied to the gear 22 to check the motor. This is accomplished by a lever 76, pivoted on the arm 36 at pivot 78, which can swing downward so as to drop into the path of the teeth on feed gear 22. The movement of this lever 76 is ef-

5 fected by a link 80 connecting its outer end to the yoke arm 62. When the latter is in its dotted position P1, the lever will engage the gear 22, as indicated in Figure 7, and quickly stop the motor.

10 When feeding material on which a very light tension is to be imposed, the combined weight of the element 26, yoke arm 62, resilient strip 66, link 80, and lever 76 are relied upon to impose such tension. These respective parts rotate very 15 easily, are all very light and their total weight is not large, but even if this should impose a larger tension than desired, a light counterweight 82 may be provided on the yoke 62 as indicated in dotted outline in Figure 4. Conversely, if a 15 greater tension is desired than the weight of the moving parts mentioned will afford, a suitable weight may be added or a spring arranged to exert a pull on the yoke arm 62 in a clockwise direction. Normally, the tension and speed of the 20 yarn will hold the element 26 substantially at the full line position shown in Figure 1. If the machine using the yarn should slow up momentarily, the length of yarn between the feed gears 22, 24 and the machine would momentarily increase, but 25 this would immediately allow element 26 to swing downward and thereby move the brush end 66b of the resilient strip to a different rod 58 and reduce the speed of the motor correspondingly. Likewise if the demand for yarn increases, the 30 element 26 is swung upward and the motor speeded-up. When the speed of the motor is thus established corresponding to the demand for the yarn the motor will continue at this speed until another variation in demand occurs. In 35 thus changing the speed of the material in accordance with the demand therefor, the tension on the material remains substantially uniform.

40 Should the machine stop, and the yarn beyond the eye end 26' cease to move, the element 26 will promptly swing downward to the dotted position P1, open the circuit to the motor 28, and apply the brake 76 to gear 22. Upon the machine being again started the pull on the yarn will raise element 26, release the brake 76, and again establish the circuit through the motor so that the latter will again drive the gears to positively feed the yarn at the proper speed as determined by the demand. In case the yarn between the gears 22, 24 and the machine should break, the element 26 will drop immediately to the dot-and-dash line position P2 shown in Figures 1 and 5. As it passes the dotted position P1, the circuit to the motor will be broken and the brake applied to the gear 22. Just before reaching the dot-and-dash position P2, the yoke arm 62 strikes a rod 84 and pushes it to the left to open a stop motion switch 86 associated with the main power circuit to the machine. This will cause the latter to stop and a similar stoppage will occur if the supply is allowed to run out and the end of the yarn passes out from between the feed gears.

45 In Figures 9 and 10 there are shown grooved rolls 22' and 24' in place of the feed gears 22 and 24 of the apparatus hereinbefore described. 50 These are particularly suited to the feeding of thin rubber yarn A' which is subject to a light tension. A modified arm 36' is mounted on the bracket 30, and grooved pulleys 88 and 90 are provided on the shafts of the feed rolls so that the upper feed roll 22' may be driven by a rubber belt 92. In this modification, it is to be noted that a braking device is not shown. This is not necessary with small rubber yarn under light 55 70 75

tension because the resilient force of the yarn, upon the circuit to the motor being broken, will impose sufficient resistance to the turning of the feed rolls to promptly stop the motor.

5 Figure 11 discloses an added feature particularly useful when the material is being fed to a machine which when starting demands immediately that the yarn assume its full normal speed of travel. Such rapid acceleration of the yarn 10 from rest to full normal speed would swing the element 26 almost instantly from its lower position, corresponding to no movement of the yarn, to its uppermost position P3, shown in dot-and-dash outline in Figure 11. Even though this 15 would by-pass the rheostat and connect the circuit direct to the motor, there would nevertheless be a momentary lag of the feed gears while the motor is getting up to speed. To avoid breakage of the light yarn, a pivoted rod 94 is provided 20 on bracket 30, having a short arm 94a engaged by a light coiled spring 96 whose strength is sufficient during ordinary feeding of the yarn to maintain the rod 94 in the full line position shown. In the event of the sudden acceleration 25 of the yarn just described, the force of this spring is temporarily overcome and rod 94 may be swung to some such position as P4 shown in dot-and-dash outline. This will occur following the movement of element 26 to the position P3. The 30 swing of lever 94 makes available for immediate travel a portion of the yarn between the feed gears 22, 24 and the machine, and this added portion, as it were, enables the motor to get up to speed before a breaking tension is imposed on 35 the yarn. As the motor speeds up, rod 94 returns promptly to its full line position and element 26 then swings downward until the normal speed of the motor is restored corresponding to the normal demand of the yarn.

40 Figures 12 and 13 show a simple attachment which may be employed with light material in lieu of a braking device for the motor. An arm 97 is mounted on the previously described arm 36 and this new arm has an arcuate portion 97a 45 on which is secured a wire 98 to form an elongated slot 100 close by a portion of the path traveled by the ring end 26' of the element 26. On the latter is added a ring 102 of rather large 50 diameter, so that when the element 26 is in its normal working range, as shown in full lines in Figures 12 and 13, the yarn A will extend from the feed gears 22, 24 directly through the ring 102 and slot 100 to the ring end 26'. Thus in 55 normal movement of the yarn the ring 102 and slot 100 play no part. But if the machine stops and there is no longer any demand by the machine for the yarn, the element 26 falls downward as previously described to effect breaking of the circuit to motor 28. Since now there is no 60 brake applied to the motor, its momentum will cause a slight overtravel after its supply of current is cut off. This causes a corresponding feeding of the yarn by the feed rolls and in the absence of the ring 102 and slot 100 might cause 65 the yarn to snarl and twist on itself. However, as the element 26 swings downward, the yarn reaches the bottom end of slot 100 and is there engaged by the wire 98. At about the same time 70 the yarn is also engaged by the ring 102. Accordingly a new loop, of a sort, is established in the yarn extending from the ring 102 to the wire 98 and thence to the ring end 26', clearly shown in heavy dot-and-dash lines in Figure 12. This 75 readily takes up the yarn fed by the overtravel

of the motor and keeps the yarn from snarling or twisting on itself.

Thus far the invention has been described in its application to the feeding of rather delicate material which can be subjected to only a very light tension. It is within the scope of the invention, however, to feed heavier material under a relatively high tension. One such application of my invention is the feeding of rubber yarn such as is commonly used in the make-up of a 10 golf ball center. Such yarn must be fed under a very considerable tension, in the neighborhood of two pounds, and this amount of tension must be maintained throughout the complete winding of the center. When the latter is started, it is 15 small in diameter but as the winding proceeds the center grows larger. The center may be rotated at a uniform speed of rotation in which case the linear speed at its surface increases as the center grows larger. Or the center may be 20 turned by a moving surface which may move at a uniform or an accelerated velocity. When this surface moves at uniform speed the surface speed of the center remains constant since it is rotated by contact with a uniformly moving surface. When the velocity of the moving surface 25 is accelerated as the center grows larger then the surface speed of the center increases and the speed of the yarn being fed to the center is an accelerated one. The adaptation of my invention to this specific problem is disclosed in Figures 14-19 inclusive, but this disclosure is to be 30 taken as illustrative of the application of the invention generally to feeding heavy material under considerable tension and at a variable 35 speed.

In the application shown, the machine 104 for winding the golf ball center C is shown on a support such as the bench 106. The golf ball center is made by winding the rubber yarn on a 40 small spherical core (not shown). This core with a convolution or two of the rubber yarn around it is placed on a belt 108 which is driven by the mechanism of the winding machine 104. This mechanism moves the belt 108 at an accelerated speed as the center of the golf ball grows 45 larger. A spring-held arm 110 with a suitable roll 112 holds the core and the wound-on yarn firmly in contact with the belt 108. Mounted on the top of the winding machine is a spool 114 of 50 the rubber yarn to be wound. The yarn is fed from the spool through a guide 116 to between a series of pairs of novel feed gears, 118, 120, thence downward around a roll 122 at the end of a relatively long lever 124, and then upward around 55 a guide roll 126 to the center.

As best seen perhaps in Figure 16, the motor 28 is mounted at the edge of the bench 106 with its shaft extended therebeyond. Close by the hub of the motor, on its shaft, is a small brake 60 drum 128 around which extends a brake strap 130, one end of which is securely fastened at 132 to the bench and the other end of which is attached to the long arm 134a of a short bell-crank lever 134. The short arm 134b of this 65 crank is engaged by a spring 136 suitably anchored at 138. The long arm 134a of the bell-crank carries a rod 140 which extends downward through a strap loop 142 on the lever 124 and terminates in an enlarged end 140a. This forms 70 a seat for a spring 144 coiled about the rod 140, upon which is a washer 146 arranged to be engaged by the lever 124. As will later more particularly appear, upon the lever 124 falling and engaging the washer 146, the rod 140 is pulled 75

downward to swing the bell-crank 134 and apply a braking force by way of the strap 130 to the brake drum 128 of the motor.

Beyond the brake drum on the motor shaft is secured a driving gear 148 which meshes with another gear 150 mounted on a sub-shaft 152. Beyond these gears, on each shaft, are the novel feeding gears 118, 120 for the rubber yarn. Each feed gear (see Figure 17) is in essence a deeply grooved pulley preferably made in two parts. Each tapered surface of each part is provided with teeth which partly intermesh when the two parts of the gear are brought together. The yarn passes through the guide 116, thence nearly around the feed gear 118 and then partly around the other feed gear 120. As it sinks in between the intermeshing teeth of the feed gears it is firmly grasped thereby and positively fed.

From the feed gears the yarn goes to and partly around the roll 122 on the lever 124. This lever is secured to a short shaft 160 suitably journaled on a standard 106a on the bench. (See Figure 19.) On this shaft is also secured a gear 162 and a drum 164. A strap 166 attached to the drum extends downward to a spring 168, the other end of which is suitably anchored. By selecting a spring of proper strength, any desired tension may be imposed on the yarn, since the spring tends to swing the lever 124 downward against the resistance offered by the portion of the yarn which is between the feed gears 118, 120 and the center C.

The gear 162 on the lever shaft 160 meshes with a much smaller pinion 170 mounted on a shaft 172 of insulating material which extends through a bracket journal 174 on the standard 106a. On the left end of this shaft 172, as seen in Figure 18, is secured the yoke arm 62, hereinbefore described. On the axle 56, (coaxially arranged with the shaft 172) is the insulated hub 46 carrying the bars 58, connected as before described (but not so shown in Figures 18 and 19) to the rheostat 44. The resilient brush strip 66 is mounted on the yoke arm 62 as before, and proper wires lead from the rheostat to the motor. Thus it is that as lever 124 swings and rotates gear 162, the pinion 170 and yoke arm 62 are rotated to cause the brush strip 66 to contact with different bars 58 and thus vary the current supply to the motor and thereby alter its speed.

Should the yarn break, or for any reason should the winding machine stop, the lever 124 swings downward and, by virtue of the gears 162 and 170, yoke 62 and strip 66, breaks the circuit to the motor. At the same time the downwardly moving lever 124 engages the washer 146 and through spring 144 pulls the rod 140 downward and applies the brake to the motor thus stopping it promptly.

As the center of the ball grows larger, the speed of travel of the yarn becomes greater. This causes lever 124 to swing upward and thus increases the speed of the motor and the feed of the yarn. While this upward swing of the lever does to some extent increase the pull on spring 168, it does not materially alter the tension on the yarn, because the moment arm of the spring with respect to the fulcrum is so short, that the slight increased tension in the spring is negligible. Accordingly, it follows that regardless of the speed of the yarn, the tension imposed upon it is substantially uniform throughout the entire winding of the center.

I claim:

1. Feeding apparatus for feeding material un-

der substantially uniform tension comprising geared elements positively engaging the material to draw it from a source of supply and to feed it; means for driving said elements comprising a variable speed electric motor; means creating a demand for said material; control means for altering the speed of said driving means including an element engaged by the material and moved thereby rotatably about an axis in accordance with the demand therefor, a series of contact wires distributed about said axis and individually connected to a rheostat, there being a contact brush carried by said element and rotatable therewith to make contact with only one of said contact wires at a time whereby the power input to said motor is varied according to the movements of said element to vary the speed of said driving means and braking means for said feeding apparatus controlled by the material and arranged to interlock with a geared element.

2. Feeding apparatus for feeding material under substantially uniform tension comprising elements positively engaging the material to draw it from a source of supply and to feed it; a variable speed motor for driving said feeding elements; means creating a demand for the material; control means for altering the feeding speed of said feeding elements in accordance with the demand for the material; said control means including a rheostat for varying the effective power input to said motor, a rotatable element engaging the material and rotated thereby as the demand for said material varies and means rotatable by and with said element to vary the effective resistance imposed by said rheostat thereby to vary the speed of the said driving means, a slotted guide for the material along which said rotatable element moves and means on said rotatable element cooperating with said guide only upon rotation of said element beyond a predetermined position for increasing the slack of the material held by said rotatable element.

3. Feeding apparatus for feeding material under substantially uniform tension comprising means creating a demand for said material; geared feeding elements capable of positively engaging the material to draw it from its source of supply and to feed it; an electric motor driving said elements; a rheostat controlling the current supply to said motor and thereby its speed; means including a pivoted element engaged by the material and moved thereby in accordance with variations in the demand for the material; and means associated with said element close by its axis of rotation and affected by the movements of said element to cause a change in the effect of said rheostat to vary the speed of said motor in accordance with said demand and thereby maintain a substantially uniform tension in the material and braking means for said feeding apparatus controlled by the material and arranged to engage a tooth of a geared element.

4. Feeding apparatus for feeding material under substantially uniform tension to a machine which demands the material, comprising geared feeding means positively engaging the material between its source of supply and its entry into the machine; a variable speed motor for driving said feeding means; braking means for said feeding apparatus controlled by the material and arranged to interlock with a geared element and control means including an element engaging the material between the feeding means and machine and adapted to be actuated by variation in the demand for said material to effect a correspond-

ing variation in the speed of said driving means whereby the speed of travel of the material is adjusted to maintain substantially uniform tension in the material being fed, there being a series of separate electrical conduits having terminals distributed about the axis of rotation of said element and means moved by the rotation of said element to establish connection between one of said series of conduits and a source of electrical supply, and means associated with said series of conduits for changing the power input to said motor in accordance with the particular circuit established by rotation of said element.

5. Feeding apparatus for feeding material under substantially uniform tension while supplying a variable demand comprising feeding means having rotating surfaces positively engaging the material to feed it; a variable speed motor connected to said feeding means to rotate the said surfaces; means for varying the current input to said motor to thereby vary its speed including

an element pivoted on an axis and having a relatively long feeler arm arranged so that its end engages the material and is rotated thereby in accordance with changes in the demand of said material, and a series of separate conduits having an end of each terminating close by the axis of rotation of said feeler element and means actuated by the rotation of said element to establish connection between one of said ends and a source of electrical power, the effective power input to said motor being determined by the connection thus established thereby causing the motor to vary its speed and the speed of the feeding means to supply the material in accordance with the variable demand, a slotted guide for the material along which said pivoted element moves and means on said pivoted element cooperating with said guide only upon pivoting of said element beyond a predetermined position for increasing the slack held by said pivoted element.

ROBERT H. LAWSON.
